BUCKLE FOR HOSE SUPPORTERS,
SUSPENDERS, OR THE LIKEWallace F. Fassett, Derby, Conn., assignor to The
Ansonia O & C Company, Ansonia, Conn., a cor-
poration of Connecticut

Application April 13, 1933, Serial No. 665,857

1 Claim. (Cl. 24—184)

This application relates to buckles, and more particularly to that style of buckle which employs a fixed or body portion having a movable part hingedly connected thereto with provision for clamping between the movable and fixed members a strip of web or fabric. Such buckles are commonly used with hose supporters, suspenders, and the like, and one requirement of such devices is that they may be made to lie as flatly as possible upon the fabric or web.

The movable part of such buckles is usually arranged so that it is in effect moved past a dead center position when closed, so that a pull on the web to which the buckle is secured will not tend to cause it to open. The opening of the buckle is usually accomplished by slipping the end of the finger or finger nail beneath the movable or hinged part and raising it upwardly or swinging it about its pivot so that the web or fabric is released. As the front plate portion is usually so shaped that it will lie flatly against the fabric and not protrude, it is sometimes difficult to insert the finger or finger nail below the plate, and for this reason gives considerable annoyance to the wearer when an attempt is made to open the buckle.

One object of this invention is to provide a buckle of the character described which may be opened readily by, and without annoyance to, the operator.

Another object of the invention is to provide a buckle for suspenders, garters, or the like, such that the buckle will lie flatly against the web or fabric to which it is connected, and at the same time may be readily engaged by the finger or finger nail when it is desired to open the same.

A still further object of the invention is to provide a buckle of the character described with a manually engageable member or lip connected to the hinged or movable portion of the buckle, this connection permitting the lip or manually engageable member a certain amount of play, so that while it may lie closely against the fabric when the buckle is closed, it may also be moved away from the fabric to allow the insertion of the finger or finger nail thereunder prior to the opening of the buckle.

A still further object of the invention is to provide the hinged or movable portion of the buckle with a manually engageable member for manipulating the same, the manually engageable member being movably connected to the hinged portion.

To these and other ends, the invention con-

sists in the novel features and combinations of parts to be hereinafter described and claimed.

In the drawing:

Fig. 1 is a front elevational view of a hose supporter having my improved buckle mounted thereon;

Fig. 2 is a side elevational view of the same;

Fig. 3 is an enlarged sectional view on line 3—3 of Fig. 1;

Fig. 4 is an enlarged detail view of the front plate of the buckle and the associated parts;

Fig. 5 is a reverse view of the front plate partly in section taken on line 5—5 of Fig. 4; and

Fig. 6 is a detail view of the body or fixed portion of the buckle.

To illustrate a preferred embodiment of my invention, I have shown a buckle comprising a fixed or body portion 10, the lower end of which is bent rearwardly and upwardly, as shown at 11, 75 and crimped about the end of the web or fabric 12 to which the buckle is designed to be connected. The body portion of the buckle is also provided with a bar 13 connected to the portion 10 by end members 14. It will be understood 80 that it is the usual practice to provide all of the aforesaid parts as one integral structure, the metal being cut away to provide the end pieces 14 and the opening 15 between the bar and the member 10. It will be understood that the web 85 or fabric is designed to be passed through the opening 15 and gripped therein, as will be hereinafter explained.

Pivotaly connected to the body portion of the buckle previously described is a hinged portion 90 comprising the front plate 16 and a gripping or jaw member 17. At the ends of the jaw member the metal thereof is slit and bent inwardly against the front plate member to provide an eye 18 at each side of this portion of the buckle. 95 These eye members embrace the bar 13 adjacent the ends thereof and form the pivotal connection between the front plate 16 and the body portion 10.

As shown in Fig. 3, the web or fabric is passed 100 through the opening 15 between the portion 10 and the bar 13 and is loosely and slidably received in this opening so that the buckle may be adjusted to any position desired along the fabric. When the front plate portion is pressed inwardly against the fabric, the gripping or jaw member 17 will bite into the fabric to some extent and clamp it against the body portion 10 so that no movement of the web through the opening 15 will be permitted. This is the posi- 110

tion shown in Fig. 3 and it will, of course, be understood that the front plate member may be moved outwardly to move the jaw member 17 from a position opposite the body portion 10 and thus release the fabric. As it is necessary to insert the finger or finger nail below the front plate 16 in order to do this, it has been found practically impossible to make a buckle wherein the front plate will lie closely against the fabric with which the buckle is used, and at the same time permit the ready and easy manipulation of the hinged member to release the fabric and adjust the buckle.

In order to accomplish this result, I have provided a lip or manually engageable member by which the front plate member may be manipulated, the manually engageable member being hingedly connected to the front plate so that it may lie closely against the fabric and be moved outwardly to a position where the finger or finger nail may be inserted thereunder. This manually operable member also serves to raise the front plate, but a limited movement of this member is permitted prior to the beginning of the raising action so that the member may be easily moved from its position against the fabric and the end of the finger inserted thereunder to move the front plate member and open the buckle.

In the form shown, the manually engageable member comprises the lip 20 having a bar 21 received in trunnions 22 formed on the reverse side of the front plate member 16. It will be observed that the bar 21 is flat and the trunnions 22 are so shaped that the lip member 20 may be moved between the full and dotted line positions shown in Fig. 4 without moving the front plate member 16. When in the dotted line position shown in Fig. 4, further movement of the lip 20 to the left is prevented by the lug 23 on the bar 21 striking the rear face of the member 16. This will be the ordinary position of the lip member when the buckle is closed, and the lip member will lie tightly against the fabric.

If it is desired to open the buckle, the lip member may be moved from the dotted line to the full line position shown in Fig. 4. This movement will be accomplished without movement of the member 16 and will move the lip member 20 away from the fabric so that the finger may readily be inserted thereunder. At this point the bar member 21 will bind in the trunnions 22 and further movement of the lip member will move the front plate member therewith and effect the opening of the buckle. It will be understood that the bar member 21 will, as shown in Fig. 4, engage at its lower end against the front plate member 16 and bind at its upper end upon the inner surface of the trunnions so as to limit the relative movement between the front plate member and the manually operable lip.

While I have shown and described a preferred embodiment of my invention, it will be understood that it is not to be limited to all of the details shown, but is capable of modification and variation within the spirit of the invention and within the scope of the appended claim.

What I claim is:

In a buckle, a body portion having an opening to receive a strip of fabric, a plate portion hinged to the body portion and designed when moved downwardly to cooperate therewith to grip the fabric therebetween, a manually engageable member movably connected to said plate portion by which the latter may be manipulated, said member being movable relatively to the hinged portion to lie closely against the fabric or to be raised therefrom for insertion of the finger therebetween, means for connecting said member to the plate portion comprising trunnions on one of said parts and a bar on the other part received in said trunnions, and stop means for limiting the movement of said member relatively to the plate portion in an upward direction to a position wherein the member is substantially in the plane of the plate portion.
